CHARLES E. JENSEN, OF PORTLAND, OREGON, ASSIGNOR OF ONE-HALF TO A. H. WETHEY,
JR., OF PORTLAND, OREGON

CABLE CLAMP

Application filed April 28, 1930. Serial No. 448,003.

This invention relates generally to the use of wire cables, and particularly to a cable clamp whereby an object may be securely fastened to the bight of a line.

5 The main object of this invention is to provide a special form of cable clamp whereby a block or other object may be movably fastened to the bight of a line.

10 The second object is to so construct the clamp that its use will in no way cause undue wear or injury to the supporting cable.

The third object is to so construct the clamp that its grip on the line will increase with the load supported by the clamp.

15 The fourth object is to so construct the clamp that it will be a simple matter to free it from the line and to hold it in the manner which will permit its being moved manually or by power to a new position.

20 The fifth object is to so construct the clamp that its holding action will not be affected by any change in the direction of pull.

These, and other objects, will become more apparent from the specification following or 25 illustrated in the accompanying drawing, in which:

Figure 1 is a perspective view showing a loading operation in which logs are being placed upon railroad cars.

30 Figure 2 is a side view of the clamp.

Figure 3 is a section taken along the line 3—3 in Figure 2.

Figure 4 is a perspective view of the wedge for holding the clamp in a sliding position.

35 Similar numbers of reference refer to similar parts throughout the several views.

In order to illustrate this invention there is shown a log loading operation including a spar tree 10 which is held by a number of

40 guy lines 11 to the stumps 12. To two of the guy lines 11 are attached the clamps 13 which I am about to describe, from which clamps are suspended the blocks 14 through which pass the log handling lines 15 which

45 are operated by the drum 16 of the donkey engine 17. The lines 15 have attached to their ends the grapples 18 by means of which the logs 19 are picked up and placed on the trucks 20 resting on the track 21.

50 Referring directly to the invention, which

is the clamp 13, same will be seen to consist of a longitudinal grooved line engaging member to which is attached a pair of forked jaw operating arms 22 whose forked sides straddle the clamp 13 and are hinged thereto by means of the pins 23. Between the forked sides of the arms 22 are placed the cable gripping jaws 24 which are secured to the arms 22 by means of the pins 25.

55 The jaws 24 are provided with a grooved face 26 and the clamp 13 is provided with a groove 27 which is preferably rounded at its ends to avoid forming into short kinks in the cable 11. The jaws 24 have formed in their adjacent faces 28 the notches 29 into which 60 may be inserted the edges 30 of the wedge 31 for the purpose of holding the two jaws 24 as far apart as is necessary to free the cable 11 for moving purposes.

65 Between the forked sides of the arms 22 are the trunnions 32 through which passes the bolt 33 whose nut 34 is tightened when the clamp is suitably positioned to prevent any possibility of same becoming free if the load is suddenly removed from the clamp.

70 For lighter operations the bolt 33 can be replaced by a spring which can be hooked between the trunnions 32 for the purpose of urging the jaws 24 to a clamping position.

75 To the closed end 35 of one arm 22 is attached a block 36 around which passes the load supporting cable 37, one end of which is attached by means of a clevis 38 to the end 39 of the second arm. Obviously, any load applied to the cable 37 will tend to draw 80 the arm ends 35 and 39 together with the degree of severity proportional to the load.

85 It is desirable on the larger sizes of clamp to provide an eye 40 for the purpose of attaching a cable 41 whose function it is to assist in moving the clamp along the line and to hold it on slopes until a load can be imposed on the clamp. It will be understood that it is now the common practice to so support the blocks, the difficulty being that the movement permitted to the block causes a rapid wear on the cable and the ultimate destruction thereof.

90 With the device above described it is possible to securely position the block at any 95 100

desired point from which it cannot move until such movement is permitted.

It will also be clear that the movement between the ends 35 and 39 can be accomplished by means of a pair of links or chains attached to those members and then joined to each other at a point where the cable 37 is attached, but it is thought that the arrangement described is preferable in most cases.

10 I claim:

1. A cable clamp having in combination a longitudinal clamp member adapted to ride upon a cable, a pair of arms hinged to said clamp member, a cable gripping shoe hinged to each arm on the under side of said clamp member, and a load supporting cable attached to the ends of said arms whereby a load supported thereby will draw said arms toward each other and force said cable gripping shoes toward said clamp member.

2. A cable clamp consisting of a longitudinal clamp member adapted to ride on the top side of a cable, a pair of shoes movable with relation to each other and to said clamp member adapted to bear against the under side of the cable, a lever arm between each shoe and the clamp member, a load supporting means suspended by the lower ends of said lever members adapted to draw same toward each other for the purpose of urging said shoes toward said clamp member, and means for holding said levers in a cable gripping position.

3. In a cable clamp the combination of a longitudinal grooved clamp member adapted to ride on a cable, a pair of cable gripping shoes on the under side of the cable, a pair of lever arms each of which has one end hinged to said clamp member and its mid section hinged to one of said shoes, a cable and pulley attached to the opposite ends of said arms for drawing the lower ends of same toward each other to a cable gripping position, and a bolt secured across the lower ends of said arms for preventing the separation thereof when a load is suddenly removed therefrom.

4. The combination of an elongated grooved clamp member adapted to ride on one side of a cable, a pair of shoes adapted to bear against the opposite side of said cable, a pair of arms hinged to opposite ends of said clamp and hinged at their mid sections to said shoes, the hinges for said shoes lying closer together than the hinges to said clamp, means for holding said shoes apart for the purpose of freeing the cable, means for drawing said arms to a cable gripping position when a weight is supported thereby, and a bolt across said arms adapted to hold same in the position to which they are moved by said weight supporting member.
